UNITED STATES PATENT OFFICE.

GUSTAV DAVERIO, OF ZURICH, SWITZERLAND.

DRIVING-GEAR FOR FLOUR-SIFTERS.

SPECIFICATION forming part of Letters Patent No. 380,249, dated March 27, 1888.

Application filed February 7, 1888. Serial No. 263,237. (No model.) Patented in Belgium October 27, 1887, No. 79,325.

To all whom it may concern:

Be it known that I, GUSTAV DAVERIO, a citizen of Switzerland, residing at Zurich, Switzerland, have invented new and useful Improvements in the Driving-Gear of Flour-Sifters, (for which Letters Patent have been granted in Belgium, October 27, 1887, No. 79,325,) whereof the following is a specification.

My invention relates to flour-sifters having quickly-rotating beaters and two slowly-rotating sifting-cylinders placed one within the other, and its object is to transmit motion from the beater-shaft to the said cylinders by means of a single strap and worm-gear.

On the annexed sheet of drawings is represented a sifting-machine provided with the mechanism by means whereof I attain this object.

Figure 1 is a longitudinal sectional view of the machine; Fig. 2, an end view, and Fig. 3 a portion of the plan.

a is the shaft carrying the beaters *b*.

c and *d* are the two cylinders.

The shaft *a* is driven by means of a pulley, *e*, fixed to one end of the same. Upon the other end of the shaft is keyed the small pulley *f*, and on the boss of the cylinder *c* the large pulley *h*, placed at some distance from the former. The boss of the cylinder *d* carries the

worm-wheel *k*. Below the said pulleys *f* and *h* two guide-pulleys, *g* and *m*, are arranged in an oblique position, and a strap, *r*, bent around the pulley *f*, is conducted on both sides of same downward and passed around the pulleys *g* and *m*, and from these upward around the pulley *h*. By these means motion is conveyed from the beater-shaft *a* to the cylinder *c*, the speed of rotation being at the same time reduced in proportion to the ratio between the diameters of the pulleys *h* and *f*. For operating the cylinder *d* the axle of the guide-pulley *g* is fitted with a worm, *i*, which gears with the worm-wheel *k*.

I claim as my invention—

The combination, with the two cylinders *c* and *d*, the beaters *b*, and the shaft *a*, of the pulleys *f* and *h*, the guide-pulleys *g* and *m*, the strap *r*, the worm-wheel *k*, and the worm *i*, fixed to the axle of one of the guide-pulleys, substantially as and for the purpose described.

In testimony whereof I have hereunto set my hand in the presence of two subscribing witnesses.

GUSTAV DAVERIO.
